UNITED STATES PATENT OFFICE

BERNHARD MATUSCHKA, OF TERNITZ, AUSTRIA

MOLD FOR INGOTS

Application filed September 9, 1931, Serial No. 561,954, and in Austria July 22, 1929.

This invention relates to ingot molds for casting metal blanks for railway wheels, tyres, and the like, and has for its principal object the provision of a mold so constructed that 5 the size of the shrinkage cavity or pipe formed in ingots cast in the mold will be reduced to a minimum and whereby excellent quality and uniformity of the finished article will be ensured.

10 Further objects of the invention will be apparent from the following description taken in connection with the accompanying drawing, in which

Figure 1 is a vertical sectional view through an ingot mold constructed in accordance with the principles of the present invention; and

Figure 2 represents a slightly modified form of mold.

For making high-grade cast ingots, it is 20 known that certain favourable conditions must be adhered to. In order to obtain an ingot as compact and as free from defects as possible with the most favourable arrangement of the pipe, it is preferable to select an 25 ingot mold which is wider at its upper end in order to facilitate after-flow of the molten steel into the solidifying ingot. When this measure cannot be adhered to or in order to further assist it, methods and means are 30 used whereby the cooling of the upper part of the ingot is retarded as much as possible, that is to say, the steel in the ingot head is kept molten as long as possible. Such methods consist in the lining of the upper part of the 35 ingot mold with refractory materials, or the placing of special refractory covers on the ingot molds. Numerous proposals have been made for improving the effects of these refractory linings or covers, for cheapening 40 their manufacture and for reducing the weight of the useless ingot head. The endeavours aim more particularly at concentrating the unavoidable shrinkage cavity (pipe) in the uppermost part of the ingot 45 head and causing the said pipe to have as wide and as short a form as possible.

The economical and material advantages of the short and wide form of pipe concentrated in the upper part of the ingot follow 50 necessarily from the nature of the subsequent

working by forging or rolling, in which the ingots mainly undergo stretching in the direction of ingot axis. The portion of the ingot head which must be removed either before or during manufacture in order to obtain a perfectly pipe-free ingot body is then 55 low in weight, so that the yield is increased.

The requirements which ingots (blanks) for the manufacture of railway wheel tyres, rings and like forged pieces must satisfy, 60 with regard to their working up, differ fundamentally from those discussed in the foregoing. As is known, an annular shape is formed by first pressing down the blank in the direction of its axis and then punching 65 out the middle portion, which operation is intended to remove the pipe at the same time.

For making wheel tyres and the like, the following two ingot molds are usually employed:

The first mold is a more or less cylindrical ingot mold open at the top and has a usually rounded bottom or even no bottom, and the ingot may be cast both from below and from the top. Usually, a refractory cover is not 70 employed. The wide pipe cavity formed with this ingot mold is pressed (welded) together as well as possible in the subsequent hot working, that is by pressing down under the hammer or press, but the pipe can never 75 be completely removed however, on punching out. This sometimes results in very considerable deficiency. The pipe formation, which is not only wide but in addition is mostly also considerably non-central, renders 80 it unavoidable that portions of the pipe are left in a more or less welded state in the finished tyre. Finally, the impurities rising in the steel, such as particles of fireclay and slag, deoxidation and segregation products, 85 collect in this mold in the wide top, that is, in a part of the ingot which later jointly forms the surface of the finished tyre, and this frequently leads to defects and flaws, 90 rendering the tyre wholly or partly useless. The extensive use of this mold is mainly due 95 to the fact that by casting the steel to different depths, blanks of any desired weight may be made, a requirement which is a consequence of the large number of rings and types 100

of tyres, so that the latter can be made with one or two sets of ingot molds of different sizes.

The difficulties which are caused in manufacture by the non-central position of the pipe and by the unsatisfactory surface quality, are often met by a sharp constriction of the top edge of the ingot mold. This entirely closed mold with the constricted upper part and rounded bottom and in which the ingot may be cast from the top or from the bottom, centres the pipe better than the mold hereinbefore discussed. Sharply constricting the upper part does not, however, always enable the non-central position of the pipe to be avoided altogether, while the pipe still always extends so considerably in width that its complete removal cannot be ensured. This mold has the great disadvantage that one special sort of ingot mold must be used for each weight of ingot desired, so that for the usual weights, 12 to 18 different sets of ingot molds must be kept in stock.

The present invention relates to an ingot mold (see Figure 1) which, due to its peculiar character, surpasses the advantages of both the usual ingot molds and also embodies a number of additional advantages without, however, involving the disadvantages described in the foregoing. The inventor has found that, in order to permit complete removal of the pipe on punching out, the said pipe must have a narrow and long form instead of the wide and short form, and hence in order to attain the desired result, the method which must be employed is just the opposite to the method otherwise usual and preferable for the manufacture of ingots for other products. Further, the inventor has found that, by the known use of rings of different height for varying the ingot weight, in connection with the new ingot mold in the arrangement shown in Figure 1, very considerable economical and industrial advantages may be secured in the present instance.

The ingot mold according to the present invention is bottle-shaped and preferably comprises an upper portion or mold member *a* which is open at the bottom, and a number of rings *B* of any height adapted to be placed below the mold member *a*.

The opening of the ingot mold is directed downwardly in such a way that its shape tapers gradually upward and is considerably bottle-shaped, while passing downwardly into a cylindrical shape.

One constructional form is, for example, such that the upwardly gradually tapering end continues further in the form of a plug, which is so dimensioned that it may be knocked off by hand.

In the new mold the pipe *c* is located exactly in the middle. The gradual taper, which begins quite soon, also causes the pipe to assume a very particularly narrow and long

shape so that it can be punched out during manufacture with the greatest certainty and a minimum of punching weight.

The gradual taper also causes the rising impurities to be carried successively towards the middle of the ingot and not to remain caught on the wall of the ingot mold. The impurities, i. e. fireclay and slag particles, deoxidation and segregation products, readily collect in the upper and very narrow part of the new ingot and are readily removed on punching out. In particular, in the constructional form described, most of the impurities are concentrated in the plug, which is knocked off before the working up, so that such a blank represents the most satisfactory raw product conceivable.

The pointed form of the ingot mold causes, on solidification of the ingot, a very quick and ready separation of the ingot from the mold, which produces a very favourable crystallization and has an extraordinarily favourable effect on the durability of the ingot molds.

With regard to the strict requirements imposed on railway rolling stock made with these ingot molds, it must be emphasized as a particular advantage that the ingot mold according to the invention produces ingots which, on hot working, undergo in that part which, according to experience is the worst part of any steel ingot, viz. near the pipe, and in the present instance therefore in the pointed upper end, the most thorough heating due to the small diameter of the said part, and the greatest compression or forging due to its greatest height in the ingot. This feature ensures the excellent quality and uniformity of the finished tyre or forged piece.

A special part of the invention are the rings *R*₁, *R*₂, *R*₃, and *R*₄ of any height which, making an exact fit, are placed under the ingot mold described in the foregoing, as shown in Figure 2 of the drawing. In addition to the advantages enumerated, the rings permit blanks of any desired weight to be made with the same ingot mold. For this purpose, it is merely necessary to place a suitable number of rings on supports. These rings occupy a small space as they can be piled easily one on the other. They represent only a small weight, as the individual rings weigh very little. By this means, the casting of ingots of different weights, for which heretofore a stock of ingot molds of 12 to 18 sorts was necessary, can be effected with 1 to 2 sorts and a suitable number of rings. Finally, the production of these rings according to the invention is exceedingly simple. It is not necessary to keep in stock numerous rings of different heights.

It suffices to keep in stock long pipes of the internal and external dimensions of the rings, which dimensions are the same for all rings, it being possible to cut off from the

said pipes in a few hours the necessary substitute rings of the desired height.

If several rings are used for erecting the mold, it is advisable to shape these so that the interior of the mold converges downwardly as is shown in Figure 2 of the drawing. The new mold can be cast from above or from below.

I claim:—

10. 1. An ingot mold for casting metal blanks for railway wheels, tyres, and the like, comprising a mold member having an internal cavity of a cross-sectional area gradually tapered upwardly from below a point substantially midway of the upper and lower portions of the member and merging at its upper end with a relatively constricted neck portion, whereby the shrinkage cavity is narrowed and elongated.
20. 2. An ingot mold for casting metal blanks for railway wheels, tyres, and the like, comprising a mold member having an internal cavity of a cross-sectional area gradually tapered upwardly from below a point substantially midway of the upper and lower portions of the member and merging at its upper end with a relatively constricted neck portion, whereby the shrinkage cavity is narrowed and elongated, said mold member being open at the lower end, and an annular element having an inner surface conforming substantially to the inner surface of the mold member adjacent its lower end forming a seat for said mold member to increase the capacity of the mold.
30. 3. An ingot mold for casting metal blanks for railway wheels, tyres, and the like, comprising a mold member having an internal cavity of a cross-sectional area gradually tapered upwardly from below a point substantially midway of the upper and lower portions of the member and merging at its upper end with a relatively constricted neck portion, whereby the shrinkage cavity is narrowed and elongated, said mold member being open at the lower end, and a plurality of superimposed annular elements gradually reduced in internal cross-section downwardly on which said mold is seated, the cavity defined by the superimposed elements merging with the cavity in said mold member.

In testimony whereof I have affixed my signature.

DR. B. MATUSCHKA.
